UNITED STATES PATENT OFFICE

137,450

DESIGN FOR A DENTAL FLOSS HOLDER

Clarence La Verne Fairbanks, Buffalo, Mont.

Application December 29, 1943, Serial No. 112,112

Term of patent 7 years

To all whom it may concern:

Be it known that I, Clarence La Verne Fairbanks, a citizen of the United States, residing at Buffalo, in the county of Fergus and State of Montana, have invented a new, original, and ornamental Design for a Dental Floss Holder, of which the following is a specification, reference being had to the accompanying drawing, forming part thereof.

I claim:

The ornamental design for a dental floss holder, as shown.

CLARENCE LA VERNE FAIRBANKS.
